UNITED STATES PATENT OFFICE.

ORA L. LANCE, OF FULTON, CALIFORNIA.

GARMENT PRESSER.

Application filed February 6, 1922. Serial No. 534,530.

This invention relates to improvements in pressing devices for garments, and particularly to improvements in devices for pressing trousers.

5 It is an object of the invention to provide pressing members adapted to be moistened and air openings to allow the moisture to readily evaporate.

It is also an object of the invention to provide 10 curved pressing members and means to clamp said pressing members against the garment.

Additional objects of the invention will become apparent from the following specification 15 and appended claims, the invention being illustrated in the accompanying drawing, wherein—

Figure 1 is a side elevation showing the garment presser made in accordance with 20 the invention.

Fig. 2 is a side elevation of the same showing the pressing members open to receive a pair of trousers.

Fig. 3 is a side elevation looking from the 25 side opposite that shown in Figs. 1 and 2.

Fig. 4 is a partial end view on an enlarged scale, sectionally, at line *a—a* Fig. 2.

Fig. 5 is a sectional end view of line *b—b* Fig. 1.

30 The device is comprised of a back section A, a member 1 for securing the cuffs of the trousers, and curved pressure leaves 2 and 3.

The back member A is in the form of a frame having a screen 16 and a cloth 15 stretched taut across it. One edge of the screen and cloth are secured to a strip of metal 17 which is held in a groove in strip 18 which is rigidly secured to the back member. The opposite edge of the screen and 35 cloth is secured in a like groove in strip 18' and to metal strip 17'. Strip 18' is provided with bolts 19—20—21 and 22 which are received by slots 23—24—25 and 26 in back member A. This is to permit strip 18' 40 to be drawn across the face of the back member by means of adjusting bolts 9 which pass through one end of brackets 9' for the purpose of keeping the screen 16 and the cloth 15 taut. Cuff member 1 is secured to the

45 back member A by means of spring hinges 5 and 6. Pressure leaves 2 and 3 are secured to strips 18 and 18' respectively by means of hinges 7. These leaves are curved as shown in Fig. 5 and the part which comes in contact with the garment is covered with cloth 50

or other suitable covering which may be moistened. They are also provided with a plurality of air vents 45. Reinforcing bars 10, 10', 11 and 11' are secured to the outer faces of the pressure leaves 2 and 3, one end 60 of each extending over the edges of the pressure leaves to engage lugs 13 and the other ends of each extend over the edges of the pressure leaves to help for a clamping means to force said pressure leaves against the garment. Reinforcing bars 11 and 11' are offset near their ends and overlap the opposing bars 10 and 10'. Fulcrumed to bars 10 and 10' are catches 12 and 12' adapted to engage the ends of the opposing bars and hold them 65 in their closed position. Each pressure leaf is provided with a spring 8 which, when catches 12 and 12' are released will return the pressure leaves to an open position. 70

Flat springs 14 are pivotally secured near 75 one end of the back member A and are adapted to hold the garment in its proper place until the pressure leaves are closed on the garment.

The garment presser is adapted to be 80 rigidly secured to a wall, door or similar place and the pressure leaves will normally be in an open position when not in use.

The function of the various parts will be 85 shown by the following operation of the device:

The cloth 15 covering the screen 16, also the cloth 43 and 44 covering the pressing surface of the pressure leaves 2 and 3 is moistened, the lower edge of member 1 is 90 raised by means of handle 4 and the cuffs of the trousers inserted between it and the back member A. The spring hinges 5 and 6 close member 1 on the trousers cuffs and holds them suspended. The trousers are 95 then smoothed out against the cloth and screen back 15 and 16 and flat springs 14 are turned up over the trousers to hold them in place. If the trousers are bowed at the knees the bow may be removed by grasping 100 the trousers back of the knees and drawing that part of them across the face of the presser until they are straightened; leaves 2 and 3 are then closed against the trousers, and leaf 3 closed against the trousers and catches 12 and 12' are moved into engagement with the ends of bars 11 and 11' until one of the notches in each catch pass over the end of the bar. 105

To remove the trousers the catches are re- 110

leased the leaves spring open, the flat springs turned down and the cuff member raised which releases the trousers.

I claim:—

- 5 1. A garment press comprising a base member having an opening therein covered with porous material and provided with means to tighten same, a cuff receiving member and means to normally hold same closed, 10 curved pressure leaves adapted to close thereon, means to fasten same when closed and spring means to open same when not in use.
- 15 2. A garment press comprising a base member having an opening therein covered with porous material and provided with means to tighten same, a cuff receiving member and means to normally hold same closed, curved pressure leaves having a plurality of

vents therein and provided with reinforcing 20 bars, the ends of which extend to form clamping means to secure same in a closed position.

3. A garment press comprising a base member having an opening therein covered 25 with a porous material and provided with means to tighten same, a cuff receiving member and means to normally hold same closed, pivotally mounted spring clips to clasp a portion of the garment, curved pressure 30 leaves provided with reinforcing bars having ends that overlap and are equipped with catch means to clamp same, and spring means to normally hold said leaves open when not in use. 35

In testimony whereof I affix my signature.

ORA L. LANCE.
